PACKER

Marion A. Garrison, South Pasadena, Calif., assignor, by
mesne assignments, to Johnston Testers, Inc., Houston,
Tex., a corporation of Texas

Application October 25, 1954, Serial No. 464,481

6 Claims. (Cl. 166—204)

This invention relates to a deep well packer construction. More particularly, the invention is directed to an expandable assembly for preventing the plastic end flow or extrusion of the packer rubber when the packer is subjected to high differential pressures.

It is the principal object of this invention to provide a mechanism for preventing plastic end flow, or extrusion, of a packer element, which device may be expanded from a retracted condition of relatively less diameter than a well bore or casing to an expanded position engaging the periphery of the well bore or pipe in which the packer is to be set.

Another object of this invention is to provide an anti-extrusion device according to the preceding object, wherein the anti-extrusion assembly is mechanically actuated independently of the packing element, whereby the anti-extrusion assembly may be completely expanded prior to the setting of the packing element.

A further object of this invention is to provide a packer construction as set forth in either of the preceding objects, wherein means are provided to permit reciprocating the tools to pound through a bridge in the borehole without inadvertent expansion of the packing element or the extrusion prevention device.

A preferred form of my invention is described in the following detailed specification, and illustrated by way of example in the accompanying drawings, wherein:

Fig. 1 shows a sectional view of the upper portion of a packer constructed in accordance with my invention.

Fig. 2 is a continuation of Fig. 1 and shows a sectional view of the lower portion of the packer.

Fig. 3 is a sectional view taken on line 3—3 of Fig. 2.

Figs. 4 and 5 are views of the upper and lower portions, respectively, of the packer showing the packer in an intermediate position, wherein the extrusion prevention device has been expanded with the packing element remaining contracted.

Fig. 6 is a sectional view taken on line 6—6 of Fig. 5.

Fig. 7 is a perspective view of one of the leaves of the anti-end flow assembly.

Referring now to the drawings, wherein like reference numerals are used to denote like elements throughout the various views shown, the packer comprises a central supporting mandrel 10. An upper housing, generally indicated at 11, comprising upper and lower portions 12 and 13, respectively, is telescopically mounted about the upper end of the mandrel 10. The upper portion 12 of the housing 11 is adapted to be threaded onto the lower end of a well string (not shown) by the threaded connection indicated at 14. The internal diameter of the upper portion 12 of the housing 11 is slightly larger than the internal diameter of the lower portion 13 thereof. A tubular cap 15 is threaded onto the upper end of the mandrel 10 and is adapted to abut the upper end of the lower portion 13 of the housing 11 to limit the upward movement of the housing 11 relative to the mandrel 10. The lower portion 13 of the housing 11 is provided with a plurality of longitudinally extending grooves 16. Each

2

of the grooves 16 is adapted to slidably receive a key 17 fastened to the mandrel 10, whereby the housing 11 is permitted to move longitudinally relative to the mandrel 10 but is locked against rotation relative thereto.

5 A pair of shear pins 18 initially lock the housing 11 and mandrel 10 against relative longitudinal movement.

An elastomer packing element 19 is mounted on the mandrel 10 below the housing 11. The upper end of the packing element 19 is bonded to a metallic ring 20, 10 which is connected to the lower end of the housing 11 by a split sleeve 21 held together by bolts 22. Bolts 22 extend through the split ring on cords preferably parallel to a diameter. Each bolt is inserted into a threaded aperture in the other segment. Consequently, Fig. 4 shows a side elevation of one sleeve in which the bolts do not extend through to the outside surface. An annular metal ring 23, having substantially the same diameter as the packing element 19, is keyed to the mandrel 10 adjacent the lower end of the packing element 19 by a pair of snap rings 24 and 25 fitting into suitable grooves provided in the mandrel 10 above and below the ring 23.

An second housing, generally indicated at 26, is slidably mounted on the lower end of the mandrel 10. The housing 26 is formed of two sections 27 and 28, respectively. The upper section 27 is provided with longitudinal grooves 29 containing keys 30 fixed to the mandrel 10, whereby the housing 26 is permitted to move longitudinally relative to the mandrel 10 but is prevented from rotating relative thereto. A plurality of shear pins 31 are fixed to the housing section 27 and extend inwardly therefrom into sliding blocks 32, which are slidably mounted in grooves 33 formed in the mandrel 10.

The lower section 28 of the housing 26 has an internal diameter slightly larger than the upper section 27 and slidably receives therewithin a piston head 34 threaded onto the mandrel 10. The piston head 34 is provided with the usual packing rings 35 to seal against the inner wall of the housing section 28. A mandrel extension 36, of substantially smaller diameter than the piston 34, extends downwardly therefrom and is slidably received within a central bore through a partition 37 in the housing section 28 below the piston 34. A restricted orifice 38 provides restricted fluid communication between the space 48 inside the housing 28, between the piston head 34 and the partition 37, and the well bore outside of the housing section 28. The orifice 38 is located immediately above the partition 37. As will subsequently be more fully explained, the piston head 34, fluid chamber 48 and orifice 38 provide a dash-pot assembly for retarding downward movement of the mandrel 10 relative to the housing 26.

Referring now to Fig. 2, a plurality of grooves 39 are formed in the outer surface of the mandrel 10 between the ring 23 and the upper end of the housing 26. The lower portions 39a of the grooves 39 are straight and extend parallel to the axis of the mandrel 10, and the upper portions 39b are wound around the mandrel 10 in the form of a spiral for purposes which will be herein-after set forth. A plurality of overlapping leaves, generally indicated at 40, each having a depending pivot pin 41, are spaced circumferentially around the mandrel 10, with the pivot pins 41 of each rotatably mounted in suitable sockets 42 provided in the upper end of the upper section 27 of the housing 26. Each of the leaves 40 is provided with an inwardly extending spherical dog 43, which is slidably received in one of the grooves 39.

As can best be seen in Fig. 7, each of the leaves 40 has an inner or rear portion 44, to which the pin 41 and spherical dog 43 are attached. This portion of the leaf 40 is adapted to lie closely adjacent the upper surface of the housing section 27. An intermediate portion 45

is formed integrally with the rear portion 44 and is stepped upwardly with respect thereto, so that its undersurface is in a plane slightly above the plane of the upper surface of the rear portion 44. Similarly, the front or outermost portion 46 is stepped upwardly from the intermediate portion 45, so that the plane of its undersurface is slightly above the plane of the upper surface of the intermediate portion 45.

Referring now to Fig. 3, it can be seen that when the leaves 40 are in their retracted positions, the intermediate portion 45 of each leaf overlies the rear portion 44 of the next adjacent leaf, and the front or outer portion 46 overlies the intermediate portion 45 thereof. When the leaves are in extended position, as shown in Fig. 6, the end portions 46 and intermediate portions 45 form a continuous unbroken annular ring adapted to receive therewithin the annular ring 23 and form a solid abutment completely filling the bore hole to prevent end flow, or extrusion, of the packing element 19.

In the use of the device, a tail pipe (not shown) is fastened to the lower end of the lower housing 26 by means of the thread 47. The tail pipe is either long enough to reach the bottom of the well, or is provided with any one of many well-known anchoring devices. The upper housing 11 is connected by thread 14 to the lower end of a well string (not shown) and the device is lowered into the well. Well fluid flows into the chamber 48 through the orifice 38. If the tool strikes an obstruction in the bore, it may be spudded, i. e., reciprocated to pound through the obstruction, without shearing the pins 31 and 18, since the fluid in the chamber 48 will act as a shock absorber to absorb the shock of the spudding action. The mandrel 10 is permitted some vertical movement with respect to the housing 26 without actuating the leaves 40 because of the straight portions 39a of the grooves 39. The amount of this vertical movement is limited by the length of the slots 33 in which the blocks 32, connected to the shear pins 31, ride.

When the desired location is reached, weight is set down slowly on the upper end of the tool and the mandrel 10 moves downwardly relative to the housing 26 which is supported by the tail pipe. The fluid in the chamber 48 passes outwardly through the orifice 38 into the well bore. When the top ends of the slots 33 reach the blocks 32, the pins 31 will shear. At this time, the spherical dogs 43 on the leaves 40 are just leaving the straight portions 39a of the grooves 39 and entering the spiral portions 39b thereof. Continued downward movement of the mandrel 10 relative to the lower housing 26 moves the spherical dogs 43 relative to the pivot pins 41, to pivot the leaves 40 outwardly from their retracted positions shown in Figs. 2 and 3 to their extended positions shown in Figs. 5 and 6. The ring 23 moves downwardly and seats within the ring formed by the overlapped outer and intermediate portions 46 and 45, respectively, of the leaves 40. This is the relationship shown in Figs. 4 and 5, wherein the anti-extrusion assembly is extended but the packing element has not yet been expanded. Further downward pressure causes the pins 18 to shear and permit the upper housing 11 to move downwardly relative to the mandrel 10 to expand the packing element 19.

From the foregoing description, it may be seen that I have provided a packer construction incorporating an anti-extrusion assembly adapted when expanded, to completely fill the well bore to prevent end flow of the elastomer packing element, and wherein the anti-extrusion assembly is mechanically actuated entirely independent of the setting of the packing element, whereby the anti-extrusion assembly is completely expanded prior to the setting of the packing element. It is further evident that I have provided a structure which is capable of spudding to get by obstructions in the well bore without inadvertently expanding either the anti-extrusion assembly or the packing element.

While I have shown and described the preferred form

of my invention, it is to be understood that various changes may be made in its construction by those skilled in the art, without departing from the spirit of the invention as defined in the appended claims.

Having thus described my invention, what I claim and desire to secure by Letters Patent is:

1. In a packer construction, the combination comprising a support, an elastomer packing element mounted on said support and adapted to be compressed longitudinally into engagement with a borehole wall, said support including a tubular housing, a mandrel telescopically received in said housing and arranged for relative movement thereto, an anti-extrusion device mounted on said support opposite an end portion of said packing element, said anti-extrusion device including a plurality of elements arranged circumferentially about said mandrel, each of said elements being conformed to overlap its adjacent elements and including an outer portion and an inner dog portion, means pivotally mounting each of said elements on said support at a point spaced from the dog portion thereof for movement substantially normal to the axis of said housing and mandrel between an inwardly retracted position and an extended position wherein the maximum diameter of said elements is greater than the uncompressed diameter of said packing element, and means carried by said support for engaging said dog portions and responsive to relative movement between said housing and said mandrel to move said elements from said retracted position to said extended position prior to compression of said packing element.

2. In a packer construction, the combination comprising a tubular housing, a mandrel slidably received within said housing for limited longitudinal movement relative thereto, an elastomer packing element carried by said mandrel, said packing element being adapted to be compressed longitudinally to effect expansion thereof into engagement with a borehole wall, and an anti-extrusion device received between opposing portions of said packing element and said housing, said anti-extrusion device including a plurality of equally spaced elements arranged circumferentially about said mandrel, each of said elements including an arcuate outer portion conformed to overlap its adjacent elements and an inner dog portion for engaging said mandrel, means pivotally mounting each of said elements on said housing at a point spaced from said dog portion for movement substantially normal to the axis of said housing and mandrel between an inwardly retracted position and an extended position wherein the maximum diameter of said elements is greater than the uncompressed diameter of said packing element, said mandrel including means engaged with said dog portions for pivoting said elements between said positions in response to said longitudinal movement of said mandrel relative to said housing.

3. In a packer construction, a tubular housing, a mandrel, means for slidably but non-rotatably receiving one end of said mandrel within said housing and permitting limited longitudinal movement relative thereto in either direction, said mandrel carrying at its other end an elastomer packing element adapted to be compressed longitudinally into engagement with a borehole wall, and an anti-extrusion device received between opposing ends of said housing and packing element and initially spaced from said packing element, said anti-extrusion device comprising a plurality of relatively flat leaves arranged circumferentially about said mandrel and each conformed to overlap its adjacent leaves, each of said leaves including an arcuate outer portion and an inner dog portion for engaging said mandrel, means pivotally mounting each of said leaves on said housing between the outer and dog portions thereof for movement substantially normal to the axis of said housing and mandrel between an inwardly retracted position and an extended position wherein the maximum diameter of said leaves is greater than the uncompressed diameter of said packing ele-

ment, said mandrel having a plurality of spiral grooves each slidably receiving one of said dog portions to pivot said leaves between said positions in response to said longitudinal movement of said mandrel relative to said housing.

4. In a packer construction, a tubular housing, a mandrel, means for slidably but non-rotatably receiving one end of said mandrel within said housing and permitting limited longitudinal movement relative thereto in either direction, said mandrel carrying at its other end an annular elastomer packing element adapted to be compressed longitudinally into engagement with a borehole wall and a rigid annular ring, and an anti-extrusion device received between opposing ends of said housing and ring and initially spaced from said ring, said anti-extrusion device including a plurality of equally spaced relatively flat leaves arranged circumferentially about said mandrel and each conformed to overlap its adjacent leaves and to receive said ring, each of said leaves including an arcuate outer portion and an inner dog portion for engaging said mandrel, means pivotally mounting each of said leaves on said housing between the outer and dog portions thereof for movement substantially normal to the axis of said housing and mandrel between an inwardly retracted position and an extended position wherein the maximum diameter of said leaves is greater than the uncompressed diameter of said packing element, said mandrel having a plurality of parallel spiral grooves each slidably receiving one of said dog portions to pivot said leaves between said positions in response to said longitudinal movement of said mandrel relative to said housing.

5. In a packer construction, the combination comprising a support including a tubular housing and a mandrel, said housing having an enlarged bore portion and a lateral orifice in fluid communication therewith, said mandrel including an enlarged end portion slidably received in said enlarged bore portion, an elastomer packing element mounted on said support and adapted to be compressed longitudinally into engagement with a borehole wall, and an anti-extrusion device mounted on said support opposite an end portion of said packing element, said anti-extrusion device including a plurality of elements arranged circumferentially about said mandrel, each of said elements being conformed to overlap its adjacent elements and including an outer portion and an inner dog portion, means pivotally mounting each of said elements on said support at a point spaced from the dog portion thereof for movement substantially normal to the axis of said housing and mandrel between an inwardly retracted position and an outwardly extended position

wherein the maximum diameter of said elements is greater than the uncompressed diameter of said packing element, lost motion means allowing longitudinal movement of said mandrel relative to said housing without actuating said elements, and means carried by said support for engaging said dog portions and responsive to relative movement between said housing and mandrel to move said elements from said retracted position to said extended position prior to the compression of said packing element.

6. In a packer construction, a tubular housing having an enlarged bore portion and a lateral orifice in fluid communication therewith, a mandrel extending out of said housing and having an enlarged end slidably received in said enlarged bore portion, means for slidably but non-rotatably keying said housing and mandrel together, said mandrel carrying at its other end an annular elastomer packing element adapted to be compressed longitudinally into and a rigid annular ring, engagement with a borehole wall and an anti-extrusion device received between opposing ends of said housing and packing element and initially spaced from said ring, said anti-extrusion device comprising a plurality of equally spaced relatively flat leaves arranged circumferentially about said mandrel and each conformed to overlap its adjacent leaves and to receive said ring, each of said leaves including an arcuate outer portion and an inner dog portion for engaging said mandrel, means pivotally mounting each of said leaves on said housing between the outer and dog portions thereof for movement substantially normal to the axis of said housing and mandrel between an inwardly retracted position and an extended position wherein the maximum diameter of said leaves is greater than the uncompressed diameter of said packing element, said mandrel having a plurality of parallel grooves each slidably receiving one of said dog portions, each groove including a longitudinal portion and a spiral portion, said longitudinal portions permitting longitudinal movement of said mandrel relative to said housing without actuating said leaves and said spiral portions pivoting said leaves between said positions in response to further longitudinal movement of said mandrel relative to said housing.
